UNITED STATES PATENT OFFICE.

ISAAC MILES, OF MANISTEE, MICHIGAN.

LATH-HOLDER.

SPECIFICATION forming part of Letters Patent No. 253,219, dated February 7, 1882.

Application filed August 29, 1881. (No model.)

To all whom it may concern:

Be it known that I, ISAAC MILES, of the city of Manistee, in the county of Manistee and State of Michigan, have invented a new and 5 valuable Lath-Holding Instrument, of which the following is a specification.

The object of my invention is to provide an instrument by the use of which labor may be saved and much time economized in the lathing of buildings. I accomplish this object by 10 the use of the instrument hereinafter described, reference being had to the accompanying drawings as forming a part of this description and specification.

Figure 1 is an elevation of my improved lath-holder. Fig. 2 is a sectional view on the line x x , Fig. 1; and Fig. 3 is a section on the line y y , Fig. 1, showing one of the cross-bars in reversed vertical position.

My invention is composed of three pieces of wood, preferably consisting of a main bar or shaft, in size one and one-eighth ($1\frac{1}{8}$) inch wide by three-eighths ($\frac{3}{8}$) of an inch in thickness and two feet in length, and two cross bars or pieces 20 at either end of the main shaft, in size six-eighths ($\frac{6}{8}$) of an inch wide by one-half ($\frac{1}{2}$) of an inch in thickness and fifteen inches in length. These cross-bars are fastened at their centers to the end of the main bar, giving the entire 25 instrument a length of two feet. The cross-bars may be fastened to the main bar by pinning or by dovetailing and pinning. The use of these cross-bars is to hold the lath in position while nailing them to the building. To 30 aid in this and to give the proper spaces between the laths, I have inserted in them wooden pins at spaces apart corresponding to the width of the lath, and in thickness or diameter corresponding to the spaces desired between 35 the laths to afford the clinch of the plaster. These pins are one and one-half ($1\frac{1}{2}$) inch apart and three-eighths ($\frac{3}{8}$) of an inch in diameter; but the size may be varied. They are nine in 40 number, (but the number may also be varied,) 45 which affords spaces for eight laths, and they are supplemented by as many coiled springs. These springs may be made of spring-steel or of brass, and their purpose is to press and hold tightly any laths that may be narrow and that 50 do not completely fill the spaces between the pins. By this means the laths are held tightly in position while the instrument is being moved

and placed in position for nailing the laths to the studs of the building.

There are nine holes bored through the main 55 shaft, or the same result may be accomplished by a narrow slit. These are the media by which I fasten the instrument to a stud of the building being lathed. They are bored in such juxtaposition that some one of them will come 60 over a stud when the instrument is placed in position for nailing the laths to the studs of the building. I fasten it in position by means of an awl or prick inserted into the proper hole and pricked into a stud of the building. 65

On one end of the instrument and on the outside of the cross-bar I have fastened a metallic plate, one edge of which is raised even with the ends of the pins or the thickness of an ordinary lath. The object of this plate is 70 to even the laths at the ends, so that the joints between the sections may be even, smooth, and true.

In this description and to explain my drawings, let a represent the main shaft; b , the 75 cross-bars; c , the metallic plate; d , the spring-steel or brass springs; e , the pins, and f the holes where the prick is inserted into studs of building.

Having described my invention, I desire to 80 explain briefly its use.

By the use of my lath holder the lathing of a building will be done evenly, and the spaces or cracks between the laths will be exactly the desired width, as the pieces may be made of 85 any size to suit the party most interested. Eight laths may be inserted in it at a time, and these constitute a section, and then the instrument should be removed one section, either to the right or to the left, as the operator may desire. By this means a break in joints in the lathing of the wall is made which will prevent 90 the plaster from cracking. When the instrument containing the laths is fastened by the prick to the desired stud of the building all 95 that is left to do with that section is to stick and drive the nails into the lath and studs of the building where they cross, and this can be done very rapidly. Then another section may be inserted, and so on to the end. By its use the 100 work of lathing a building is greatly facilitated.

Materials, spaces, distances, proportions, and numbers may be changed, and the instrument may be made to adjust six, eight, ten, twelve,

or any desired number of laths to the building.

Having described my invention and its use, what I claim, and desire to secure by Letters

5 Patent of the United States, is—

1. In a lath-holder, the combination, with the perforated bar *a*, of the cross-bars *b b*, each provided with pins *e* and springs *d*, substantially as described.

10 2. In a lath-holder, the combination, with

the perforated bar *a* and cross-bars *b b*, of the pins *e*, springs *d*, and metallic plate *c*, substantially as described.

In testimony that I claim the above I have hereunto subscribed my name in the presence 15 of two witnesses.

ISAAC MILES.
